UNITED STATES PATENT OFFICE.

JOSEPH M. KENNEDY, OF ST. LOUIS, MISSOURI, ASSIGNOR OF ONE-HALF TO EDWARD SPRINGMEIER, JR., OF ST. LOUIS, MISSOURI.

TELEGRAPH SENDING-MACHINE.

1,177,778.

Specification of Letters Patent.

Patented Apr. 4, 1916.

Application filed December 5, 1913. Serial No. 804,887.

To all whom it may concern:

Be it known that I, JOSEPH M. KENNEDY, a citizen of the United States, and resident of St. Louis, Missouri, have invented certain new and useful Improvements in Telegraph Sending-Machines, of which the following is a specification containing a full, clear, and exact description, reference being had to the accompanying drawings, forming a part 10 hereof.

My invention relates to improvements in telegraph sending machines, and the primary object of my invention is to construct a sending machine of the type having a vibrator for forming dots with a key which is moved vertically, so that in the formation of dots the normal or natural vertical movement of the operator's fingers sets in motion the vibrating member.

20 A further object of my invention is to construct a sending machine of the type having a laterally movable vibrating arm for the formation of dots with a key having the natural vertical movement for the operation 25 of the vibrator and to combine with this key a second key movable independently of the first mentioned key for the formation of dashes, the second mentioned key having the ordinary natural vertical movement.

30 With the above purposes in view my invention consists in certain novel features of construction and arrangement of parts as will be hereinafter more fully described, pointed out in the claim and illustrated by 35 the accompanying drawings, in which—

Figure 1 shows in plan a telegraph sending machine constructed according to my invention; Fig. 2 shows in elevation my improved sending machine; Fig. 3 is a trans- 40 verse sectional elevation of the machine taken on the line 3—3 of Fig. 1; Fig. 4 is an enlarged elevation partly in section showing the relative arrangement of the two keys; and Fig. 5 is an inverted plan of the instru- 45 ment.

Referring by numerals to the accompanying drawings: 6 designates the base constructed of material possessing electrical conductivity. Carried by the base and on its 50 underneath face are the cushioned feet 7. On the upper face of the base adjacent the forward end thereof is a yoke 8 which yoke is in electric circuit with the base.

Depending from the yoke adjacent one of

the standards thereof is an ear 9 arranged to 55 form with said upright arm of the yoke a support for a pivot pin 10. Mounted for vertical rocking movements on the pivoted pin 10 is a lever 11. At the outer or forward end of the lever 11 there is a key 12 having 60 a central vertical bore 13 therethrough. Carried by the yoke to one side of the ear 9 is a pivot bolt 14, and pivotally connected with said bolt in a manner to move in a horizontal direction is a bar 15. Carried by 65 the bar at its forward end and in the path of travel of the lever 11 is an inclined plane 16 whereby when the key 12 is depressed the lever 11 will be vertically rocked and engage the inclined plane 16 to effect a lateral or 70 horizontal rocking of the bar 15. Carried by the bar 15 through the medium of a metallic leaf 17 is a vibrating arm 18 carrying a movable weight 19. Secured to the base and arranged to engage the vibrating 75 arm 18 is a stop 20 and carried by the yoke 8 is a pair of adjusting screws 21 arranged to control the movement of the bar 15. Carried by the vibrating arm 18 is a yielding contact point 22. Arranged in the path of 80 movement of the yielding contact point 22 is a fixed contact point 23 which is insulated from the base 6.

24 designates a binding post in electric circuit with the base, and 25 designates a 85 binding post insulated from the base.

26 designates an insulated conductor leading from the contact point 23 to the binding post 25.

The means just described constitutes the 90 necessary parts for the formation of dots, and the necessary electric circuit. The means for forming the dashes comprises a plate 27 which is insulated from the base 6, but which is connected with the binding post 95 25 through the medium of an insulated conductor 28 and the insulated conductor 26, and a vertically movable contact 29 carried upon a vertically movable pin 30 in electric circuit with the base and carrying an insulated key 31 nested within the bore 13 of the key 12. The contact point is preferably secured to a collar 32 which is secured to the pin 30. Embracing the pin 30 and impinging between the collar 32 and the base 6 is 100 an extensible coil spring 33 whose office is to hold the key 31 and contact 29 in elevated 105 positions.

34 designates a stop which is secured to the base and insulated therefrom and lying in the path of the lever 11, which stop limits the movement of the lever so as not to effect 5 a movement of the contact point 29.

35 designates a switch which may be of any desired construction and is arranged to cut in and out of circuit the plate 27.

In the practical operation of my machine, 10 assuming it to be in electric circuit with a sounder and the switch 35 open, the operator places his fingers upon the key 12 and, by the regular and normal vertical movement as is used in connection with all Morse machines, depresses the key 12 when it is desired to produce dots. By the adjustment of the weight 19 and the set screws 21 the desired movement of the vibrating arm is established and the number of dots is controlled entirely by the duration of the touch 15 of the key 12. Without any appreciable shifting of the hand or any of the fingers the operator can practically through a one-key arrangement depress the key 31 and 20 establish a connection through the contact 25

point 29 and plate 27 to produce a dash or dashes.

It is obvious that both the dot and the dash are accomplished through the medium of the ordinary and natural vertical movements of the fingers and that the machine may be quickly "learned", and speed and accuracy obtained without the acquiring of a new "arm".

I claim:

A telegraph sending machine, comprising two vertically and independently movable keys, one of which keys is provided with a bore through which the other key is operable, and means associated with each key for 30 making and breaking an electric circuit, one of which means includes a vibrating element.

In testimony whereof, I have signed my name to this specification, in presence of two subscribing witnesses.

JOSEPH M. KENNEDY.

Witnesses:

E. L. WALLACE,
E. M. HARRINGTON.
